EXPOSURE TIMING MECHANISM

Roland L. Smith, Belmont, Mass.

Application January 26, 1945, Serial No. 574,662

6 Claims. (Cl. 161—1)

1

This invention relates to exposure timing mechanisms such as are employed in making photographic enlargements and prints by electric light.

A timing mechanism of the class referred to is employed for controlling and operating an electric circuit in which is arranged an electric lamp by means of which the enlarging or printing is effected and such a device is, as a practical matter, essential when a number of prints or enlargements are to be produced from a single negative if uniformity in results is to be obtained.

A well known type of timing instrument has heretofore been provided which comprised a finger-operated rotatable dial, a spring motor for yieldingly urging said dial rotatively in one direction at a predetermined speed, a switch incorporated in the circuit of the lamp, said switch including a resilient contact serving also as a stop for limiting the rotary movement of the dial under the influence of the spring motor and being normally maintained in open position by the dial, and a finger-engaging stop on the frame or base of the instrument for limiting the rotary movement of the dial in the opposite direction under the influence of the finger of the operator. The dial was made with a circular series of sockets or apertures spaced apart equidistantly at intervals of a predetermined number of seconds, usually five seconds, and in making an exposure, say for example fifteen seconds, the operator would insert his finger in the third aperture or socket in front of the finger stop and quickly turn the dial clockwise away from the switch until movement of his finger and the dial in that direction were arrested by said finger stop whereupon the operator released the dial thereby permitting the spring motor to return the same counter-clockwise to its normal position again at said predetermined speed. At the start of the movement of the dial under the influence of the operator's finger the resilient contact was released thereby closing the circuit through the lamp, and at the completion of the return movement of the dial under the influence of the spring motor the resilient contact was restored to its normally open position by the dial thereby extinguishing the lamp at the expiration of the selected interval of time—fifteen seconds.

An objectionable feature characterizing the above described and other constructions heretofore proposed has been that in making many enlargements or prints from one and the same negative it was necessary, throughout this procedure, for the operator to remember or bear in

2

mind the length of time, as measured in seconds, for each exposure since no indication of this factor could be derived from the instrument itself.

Another objectionable feature of devices of this class as heretofore provided has been that when the dial was constructed with a supplemental series of holes or sockets, more closely spaced apart than the finger holes or sockets, for use in effecting exposures differing in time from that possible through use of the finger holes, said supplemental holes or sockets were necessarily made too small for the reception of the finger so that it was necessary for the operator to equip himself with a pointed skewer-like accessory instrument such as a pencil, for example, for use within the small supplemental holes when operating the dial.

This invention has for its object to provide an improved timing instrument of the class described and in particular to obviate the above noted objectionable features characterizing devices of this class as heretofore constructed.

To this end I have provided certain improvements in instruments of the class indicated as set forth in the following description, the several novel features of the invention being separately pointed out and defined in the claims at the close of the description, it being understood, however, that the illustrated embodiments of the invention are to be taken as preferred examples of the latter and that various changes may be resorted to without departing from my invention as defined in the claims.

35 In the accompanying drawing:

Figure 1 is a top plan view of an exposure timing instrument constructed in accordance with this invention.

Figure 2 is a side elevation, partly in section, of the instrument shown in Fig. 1.

Figure 3 is a section on line 3—3 of Figs. 1 and 2.

Figure 4 is a sectional detail relating to the dial of Figs. 1 and 2.

45 Figure 5 is a partial top plan view of an exposure timing mechanism embodying an alternative form of the invention.

Figure 6 is a side view of the parts shown in Fig. 5.

50 Figure 7 is a detail hereinafter referred to relating to the embodiment illustrated in Figs. 5 and 6.

The embodiment of my invention illustrated in Figs. 1, 2, 3, and 4 of the drawing comprises 55 a molded base 10 of any suitable non-conducting

moldable material, said base being in the form of an inverted cup which provides a housing for a spring motor 11 and an electric switch comprising a fixed contact 12 and a resilient contact 13. Contacts 12 and 13 are arranged in an electric circuit 14 in series with the usual electric lamp (not shown) by means of which the photographic enlargements or prints are made from a negative or the like.

Spring motor 11 is fastened by screws 11a (Fig. 1) to the under side of the top wall of base 10 and includes a vertical shaft 15 which extends upwardly therefrom loosely through an aperture provided in the top wall of base 10 to the exterior thereof where it has fixedly mounted on it a circular molded dial 16 that is formed near its periphery with a circular row of finger holes or sockets 17 disposed concentrically with respect to the axis of motor shaft 15.

Upon its under side the dial 16 is made with a depending boss 18 which is normally pressed laterally against one side of the upper end of the resilient contact 13 by motor 11 so as to hold said contact out of engagement with the fixed contact 12. The fixed contact 12 is disposed entirely within base 10 where it is fastened by screws to a pad 19 (Figs. 2 and 3) forming part of the top wall of the base. The resilient contact 13 is fastened by screws to another pad 20 forming part of the top wall of the base and includes a free end portion extending upwardly through an aperture 21 formed in the top wall of the base to the exterior of the latter where its upper extremity occupies a position in the path of the boss 18. One side of this aperture 21 serves as a stop to positively limit the movement of contact 13 occasioned by the pressure of the boss against the same.

A bracket 22 is fastened by screws to the exterior of base 10 and the upper end portion of said bracket is made with a lateral finger-stop extension 23 which overhangs the marginal portion of dial 16 just above the path traversed by the finger-holes or sockets 17 when the dial is rotated on the axis of shaft 15.

The finger-holes or sockets 17 are angularly spaced apart relatively to each other alike throughout the row a distance equaling the angular movement of shaft 15 during a predetermined length of time as measured by a number of seconds and the angular distance between hole or socket #1 and finger stop 23 is the same.

Assuming this distance between the holes and between hole #1 and stop 23 to be equal to the angular displacement of shaft 15 and dial 16 during an interval of time of five seconds, as in the drawing, it will be clear that by inserting a finger in either one of the holes 17 and turning dial 16 and shaft 15 clockwise until movement of the finger and dial in that direction is arrested by stop 23 and immediately releasing the dial, then the spring motor will rotate dial 16 and shaft 15 contra-clockwise back to their normal positions again and this return movement will be effected by motor 11 during a period of time corresponding with the angular distance between the hole that is used and the stop 23, said period of time being either five seconds or a multiple of five seconds according to the position of said hole.

It will also be clear that during the time that the dial is away from its normal position switch 12-13 is closed and the lamp (not shown) of the apparatus is lighted. Thus, by using the proper hole or socket 17 in operating the dial

it is possible to provide for an exposure that prevails for a definite measured length of time appropriate to the characteristics of the particular negative or the like that is being employed, provided said appropriate time is five seconds or a multiple of five seconds.

The above described construction is as heretofore and serves its purpose very well when making a small number of enlargements or prints from a single negative or the like requiring comparatively long exposures, but when making a considerable number of enlargements from one and the same negative or the like, the operator would often inadvertently use the wrong finger-hole during his repeated operations of the dial because of the absence of any means for visually indicating the proper hole to use. Moreover, when operating with a thin negative requiring short accurately timed exposures other than of five seconds or a multiple thereof, it was not possible to operate the instrument accurately as required except through the use of the accessory skewer-like implement and the relatively small supplemental holes or sockets, hereinbefore referred to. My improvements, now to be described, obviate these objectionable features characterizing instruments of this kind as heretofore constructed and with which I am familiar.

In accordance with this invention I provide the timer mechanism with a finger-operated arm 24 (Fig. 1) of resilient sheet metal disposed radially above, and in close proximity to, the dial 16, said arm being pivotally secured at its inner end to the upper end of the motor shaft 15 by a screw 25 so that it is normally free to be swung laterally relatively to said shaft and the dial in either direction. The outer end of this arm is provided with a depending ratchet tang 26 (Figs. 2 and 4) to cooperate with a composite circular row or series of relatively small closely spaced sockets or recesses 27 and 28 formed in the marginal portion of dial 16 and disposed concentrically with respect to the axis of shaft 15. Each of these sockets or recesses is adapted to receive the tang 26 as shown in Fig. 4 and provides at one side thereof an abrupt abutment shoulder facing away from stop 23 and adapted to be engaged by one side of tang 26 which is parallel with said shoulder. The opposite side of tang 26 may be beveled as shown so that the tang may slide freely over the sockets when arm 24 is rotatively adjusted in that direction. The resiliency of arm 24, however, permits the free end thereof to be manually lifted away from the dial when the arm is to be adjusted in either direction.

Each socket 27 of the composite series is cooperatively associated with one of the finger-holes of the dial in that when occupied by the tang of arm 24 the latter then serves to indicate that the finger-hole associated with that socket is being used. This is an important function when a number of enlargements or prints are being made from one and the same negative since it guides the photographer in his operation of the dial and relieves him of the necessity of remembering the particular timing being employed. Arm 24 likewise serves as an indicator when engaged with either of the sockets 28.

When the dial occupies its normal position the composite portion of the supplemental row of sockets 27-28 starts at the finger-stop 23 and extends therefrom contra-clockwise around the marginal portion of dial 16 as far as finger-hole #6, an angular distance corresponding with the

distance traveled by the dial during thirty seconds while being actuated by spring motor 11 and throughout this composite portion all of the sockets are spaced apart relatively equidistantly a distance corresponding with the extent of angular displacement of dial 16 effected by motor 11 during a one second period of time.

In making enlargements from a thin negative or the like not only is much less time required than with a dense or strong one, but much finer regulation or control of the exposure period is necessary with the thinner negative or the like, which is, as will be clear, obtainable through use of arm 24 and the sockets of the composite portion of the supplemental row, the latter being spaced apart relatively one second.

When using a finger-hole or socket beyond the composite portion of the supplemental row, which will be the case in producing enlargements from a strong or dense negative or the like, the arm 24 is set in engagement with the socket 27 of the appropriate finger-hole and utilized in operating the dial. With this type of negative or the like regulation of the time of exposure to the extent of five seconds or multiple thereof is ordinarily sufficient and this is provided for by the five seconds spacing of the finger-holes that are beyond the composite portion of the supplemental row.

As shown in Fig. 2 of the drawing the stop extension 23 is disposed above the path of the dial operating arm 24 so that the latter can, at times, pass beneath the same.

In starting enlarging operations with a given thin negative the operator usually makes some preliminary trial exposures by means of the finger holes 17 and after thus ascertaining the approximate time he can then obtain the exact timing through use of the pawl-like arm 24 and the composite row of supplemental sockets 27-28. In many instances this will avoid the necessity of regulating the intensity of the light.

In the embodiment of the invention illustrated in Figs. 5, 6 and 7 the periphery of the dial 16a is made throughout its circuit with a circular row of ratchet-like teeth 29 which provide abutment shoulders 30 facing away from the fixed finger stop 23a, said shoulders co-operating with a vertically resilient pawl-like arm 24a. This arm is pivoted loosely upon the upper end of the shaft 15 of the spring motor (not shown) and held in position thereon by a nut 25a having threaded engagement with said shaft.

The teeth 29 are spaced apart relatively an angular distance corresponding with the extent of rotary motion imparted to the dial by the spring motor during one second and within this circular row of teeth 29 the dial is formed with a circular row of finger holes or sockets 17a which are spaced apart relatively an angular distance corresponding with the extent of rotary motion imparted to the dial by the spring motor during five seconds, each of said holes or sockets 17a being disposed radially opposite one of the abutment shoulders 30a of teeth 29 so that the holes of the group or row 17a serve as indicators to guide the operator in accurately placing the arm 24a in any desired position.

The free end of arm 24a is made with a depending tang 26a (Fig. 7) to co-operate with the 70

teeth 29, said tang being yieldingly held against the dial by the resiliency of the arm of which it forms part.

What I claim is:

5 1. In a timing instrument, the combination of a rotatably supported switch-operating dial whose outer marginal portion is made with a concentric row of finger-sockets angularly spaced apart equidistantly at relatively large intervals and also with a concentric row of supplemental sockets spaced apart equidistantly at smaller angular intervals that subdivide the intervals between said finger-sockets; a radial arm pivotally supported for independent rotative adjustment at times on the axis of said dial to set said arm in a definite time-indicating position relatively to said dial; a fixed finger stop, and means on said arm for engaging one of said supplemental sockets to positively adjust said dial rotatively when said arm is swung by finger pressure toward said finger-stop.

15 2. The combination of claim 1 wherein said arm is a resilient member and wherein said last-mentioned means consists of a depending tang provided adjacent to the outer end of said arm and yieldingly held in socket-engaging position by the resiliency of said arm.

20 3. The combination of claim 1 wherein said finger-stop overhangs said dial and wherein the outer end portion of said arm is movable with said dial on a path between the latter and said finger-stop.

25 4. The combination of claim 1 wherein said supplemental sockets are provided by a circular row of teeth formed upon the outer marginal portion of the dial.

30 5. The combination of claim 1 wherein said supplemental sockets are provided by a circular row of ratchet teeth formed upon the outer marginal portion of the dial, and wherein said arm is a resilient pawl-like member that is maintained in socket-engaging position by its resiliency.

35 6. In a timing instrument, in combination, a rotatably supported switch-operating dial whose outer marginal portion is made with a row of relatively large finger-sockets that are angularly spaced apart at relatively large intervals concentrically with respect to the axis of said dial, and made also with a concentric row of relatively small supplemental sockets spaced apart at smaller angular intervals that subdivide the intervals between said finger-sockets; a spring motor having a vertically disposed shaft on which said dial is fixed, said motor yieldingly maintaining said dial normally at the limit of its rotary movement in one direction; a radial finger-operated arm pivotally mounted loosely upon said shaft for independent rotative adjustment thereon at times to set said arm in a definite time-indicating position relatively to said dial; means carried by said arm for engaging one of said supplemental sockets to positively adjust said dial rotatively when said arm is swung by finger pressure in the opposite direction, and a fixed finger-stop in the path of the finger for limiting the movement of the dial in said opposite direction.

ROLAND L. SMITH.
